UNITED STATES PATENT OFFICE.

AUGUSTUS HAGER BRYANT, OF GLEN RIDGE, NEW JERSEY.

SAFETY-RAZOR.

Specification of Letters Patent.

Patented Jan. 8, 1918.

1,252,996.

Application filed June 5, 1917. Serial No. 172,909.

To all whom it may concern:

Be it known that I, AUGUSTUS HAGER BRYANT, a citizen of the United States, and a resident of Glen Ridge, in the county of Essex and State of New Jersey, have invented a new and Improved Safety-Razor, of which the following is a full, clear, and exact description.

This invention relates to razors and particularly to an improved construction of safety razor wherein a minimum number of parts are used and yet the usual effect is produced.

Another object of the invention is to provide a safety razor structure which utilizes a plastic material, as for instance, celluloid, in all the parts excepting the blade.

Another object in view is to provide a structure in which a wedge holds the blade in position.

A still further object in view is the provision of a safety razor formed with a notch in the rear edge thereof coacting with a wedge-shaped projection.

25 In the accompanying drawing:

Figure 1 is a perspective view of a safety razor embodying the invention.

Fig. 2 is a section through Fig. 1 on line 2—2.

30 Fig. 3 is a view of the razor shown in Fig. 1 with the parts slightly separated for illustrating more clearly their construction and the way they are assembled.

Fig. 4 is a top plan view of the holder.

35 Referring to the accompanying drawing by numerals, 1 indicates a handle formed in any suitable shape and preferably provided with a threaded extension 2 of the holder 3. The holder 3 is made with side members 4 and 5 having overhanging hook members 6 and 7, said overhanging hook members being resilient to an appreciable extent and coacting with a wedge 8 for holding the blade 9 in the holder 3. The blade 9 is provided with a cutting edge 10, projections 11 and 12 adapted to rest against the edges of the members 4 and 5, and a notch 13 preferably slightly larger than the notch 14 in the holder 3. The wedge 8 is

40 provided with a projection or lug 15, preferably of the same size and shape as notch 14, said lug being arranged to fit into said notch when the wedge is in position and to limit the movement of the wedge toward the edge 10 of the blade 9. Ordinarily the 45 lug 15 is not moved down to the bottom of

the notch 14 as the clamping action of the wedge is sufficient before it reaches this position, though in case of an extra heavy pressure, accidentally or intentionally, the 60 lug will limit the movement of the wedge so that the lower edge of the wedge will not cover or substantially cover the edge 11 of the blade 9.

The holder 3 is provided with guarding 65 fingers 16 which are formed with rounded ends 17 positioned near the edge 10 of blade 9 when the device is in use. Lather grooves 18 are provided in the holder 3, as shown in Fig. 4, said grooves extending along each 70 side of the respective fingers 16, so as to permit a proper discharge of the lather and to provide comparatively large recesses for receiving the lather directly from the face 75 during the shaving operation.

In constructing the parts of the razor the blade 9 is made from some good quality of steel and comparatively thin, in the usual manner of blades of this character, but without openings or notches except the notch 80 13, whereby a comparatively strong and stiff blade is produced which is braced by the holder 3 and the wedge 8. In forming the handle 1, holder 3 and wedge 8, the same are preferably formed from some plastic 85 material, as for instance, celluloid. Preferably the celluloid is white, whereby a perfectly sanitary structure is produced and one where dirt may be readily detected.

In operation, when the parts are in the 90 position shown in Figs. 1 and 2 the device is ready for use and may be used in the usual manner of safety razors. After the device has been used and it is desired to clean the same, a pressure by the thumb on the 95 wedge 8 in the proper direction will cause the wedge to slide out of the hook members 6 and 7, whereupon the wedge is perfectly loose and also the blade 9 is perfectly loose and may be washed and dried, 100 as well as the holder 3. The blade is then inserted in the holder until the members 11 and 12 strike against the edges of the members 4 and 5, and then the wedge is again inserted and pressed forward until the parts 105 are sufficiently tight. Preferably the handle 1 is held in place by the threaded extension 2, whereby the handle and the holder 3 may be separated when it is desired to store the same in a small place, though if desired the 110 handle and the holder could be molded from one piece of material. Though white cel-

luloid is preferable other materials could be used without departing from the spirit of the invention.

What I claim is:

- 5 1. A safety razor, comprising a handled holder having overhanging resilient members, a centrally arranged V-shaped recess in its face at the rear edge, curved guard fingers and a plurality of depressions at the bases of the guard fingers and opening into the spaces between said fingers, a blade having at its ends projections engaging the ends of the said members of the holder and 30 with a notch in its rear edge, and a wedge fitting under the members of the holder and having a projection fitting in the recess of the holder, the holder, handle and wedge being formed of celluloid. 35
- 10 10. bases of the guard fingers and opening into the spaces between said fingers, a blade provided at its ends with projections engaging the ends of the overhanging members of the holder and with a centrally arranged 15 V-shaped notch, and a wedge fitting under the overhanging members of the holder and having a centrally arranged V-shaped projection engaging the recess of the holder and the notch of the blade.
- 15 15. 2. A safety razor, comprising a handle having a threaded socket in one end, a holder having a reduced and threaded extension engaging the threaded socket, and provided with overhanging hook members at its sides,

a centrally arranged recess in its face at the 25 rear edge, curved guard fingers, and depressions at the bases of the fingers and opening into the spaces between said fingers, a blade having at its ends projections engaging the ends of the said members of the holder and 30 with a notch in its rear edge, and a wedge fitting under the members of the holder and having a projection fitting in the recess of the holder, the holder, handle and wedge being formed of celluloid.

3. A safety razor, comprising a holder having overhanging members, curved guard fingers, and grooves extending along the opposite sides of each finger, the grooves of each two adjacent fingers merging into a 40 groove in the body of the holder, said groove being approximately of a width equal to the distance the fingers are apart, a blade having lugs engaging the ends of the overhanging members, and a wedge fitting under the 45 overhanging members of the holder and locking the blade in position.

AUGUSTUS HAGER BRYANT.
